UNITED STATES PATENT OFFICE.

FREDERICK WESTERBECK, OF ST. LOUIS, MISSOURI.

CONTAINER.

1,166,395.

Specification of Letters Patent.

Patented Dec. 28, 1915.

Application filed July 13, 1914. Serial No. 850,631.

To all whom it may concern:

Be it known that I, FREDERICK WESTERBECK, a citizen of the United States of America, a resident of the city of St. Louis, 5 State of Missouri, have invented certain new and useful Improvements in Containers, of which the following is a full, clear, and exact description, reference being had to the accompanying drawings, forming a part of 10 this specification.

My invention relates to containers, and it has for its object the production of a strong, simple, inexpensive, and very efficient means by which the lids of such boxes 15 or cans may be readily separated from the bodies to which they are fitted. The improvement is more particularly intended for use in containers for shoe blackening or polish, but it may be used in boxes cans or 20 other receptacles designed to hold various other materials.

Figure I is a side elevation of a box provided with my lid lifting device. Fig. II is an enlarged vertical section taken through 25 the lid lifting device, a portion of the box being broken away. Fig. III is an enlarged vertical section showing the inside of the box and lid and the lever arms at the inner end of the lid lifting device. Fig. IV is an 30 enlarged fragmentary horizontal section taken through the lid, and showing the upper edge of the box body which lies directly below the lever arms of the lid lifting device. In the accompanying drawings: 1 35 designates the body of a sheet metal box and 2 the lid of said box. To provide for the application of my lid lifting device, I preferably produce in the flange of the box lid a perforation around which is a circular neck 3 which is to serve as a bearing and 40 may be produced by punching a portion of the flange inwardly.

My lid lifting device preferably comprises a single wire-like member, preferably substantially semi-circular in cross-section (Fig. II) bent to form a loop-shaped handle 4 at the exterior of the lid, and doubled intermediate its ends to produce a substantially circular stem 5 which passes 45 through the neck 3, the end portions of said wire-like member being bent laterally, away from each other, and backwardly toward the lid to overlie the upper edge of the box body. The lever arms 6, formed at the end 50 portions of the lid lifting device, preferably lie directly opposite each other so that

the lid may be released from the box body by turning the handle 4 in either direction. The ends of the lever arms 6, overlapping the upper edge of the box body, are arranged 55 within an annular groove 7 formed in the inner face of the flange of the sheet metal lid. This annular groove 7 is formed concentric with the axis of the stem 5 to receive the pair of lever arms 6, which move 60 about said axis. The annular bead 8, produced in forming the annular groove 7, serves as a seat for the handle 4, while the wall of said annular groove serves as a seat for the lever arms 6 which extend over the 65 upper edge of the box body. The strong and simple lid lifting device is thus firmly secured to the lid, and the pair of lever arms 6 are located where they will positively engage the upper edge of the box 70 body when the handle 4 is turned in either direction. Further, either lever arm is adapted to ride against the wall of the annular groove 7 while the other lever arm is serving to pry the lid from the box body, 75 thereby preventing canting of the lever which is lifting the lid of the box.

I claim:

1. The combination with a box body and a lid fitted to said body, of a single piece lid 85 lifting device comprising a handle at the exterior of said lid, and a stem extending from said handle through said lid, said stem being provided at its inner end with a pair of divergent lever arms bent laterally, away 90 from each other, and backwardly toward said lid to overlie the upper edge of the box body.

2. The combination with a box body and a lid fitted to said body, of a single piece 95 lid lifting device comprising a handle at the exterior of said lid, and a stem, circular in cross section, extending from said handle through said lid, said stem being provided at its inner end with a pair of divergent lever arms bent laterally, away from each 100 other, and backwardly toward said lid to overlie the upper edge of the box body.

3. The combination with a box body and a lid fitted to said body, of a lid lifting device 105 comprising a single wire-like member, semi-circular in cross section, bent to form a loop handle at the exterior of said lid and doubled intermediate its ends to produce a stem which passes through the lid, and lever 110 arms formed by the end portions of said wire-like member, said lever arms being

bent laterally, away from each other, and backwardly toward said lid to overlie the upper edge of the box body.

4. The combination with a box body and a lid fitted to said body, of a lid lifting device comprising a handle at the exterior of the lid, a stem extending from said handle through said lid, and a lever arm extending laterally and backwardly from the inner end 10 of said stem to overlie the upper edge of the box body, the lid being provided with a circular groove adapted to receive the end of said lever arm.

5. The combination with a box body and a lid fitted to said body, of a lid lifting device comprising a handle at the exterior of the lid, a stem extending from said handle through said lid, and a lever arm bent laterally and backwardly from the inner end of 20 said stem to overlie the upper edge of the box body, the inner face of said lid being provided with an annular groove arranged concentric to the axis of said stem and adapted to receive the end of said lever arm for the purpose described.

6. The combination with a box body and a lid fitted to said body, of a single piece lid lifting device comprising a handle at the exterior of the lid, a stem extending from said handle through said lid, the inner end of said stem being provided with a pair of

lever arms bent laterally, away from each other, and backwardly toward said lid to overlie the upper edge of the box body, the inner face of said lid being pressed outwardly to form an annular groove concentric with the axis of said stem and adapted to receive the ends of said pair of lever arms. 35

7. The combination with a box body and a lid fitted to said body, of a lid lifting device comprising a single wire-like member, substantially semi-circular in cross-section bent to form a handle at the exterior of the lid and doubled intermediate its ends to produce a substantially circular stem which 40 passes through the lid, and lever arms formed by the end portions of said single wire-like member, said lever arms being bent laterally, away from each other, and backwardly toward said lid to overlie the upper 45 edge of the box body, a portion of said lid being bent inwardly to form a substantially circular bearing for said substantially circular stem, and the inner face of said lid being provided with an annular groove arranged concentric with the axis of said stem and adapted to receive the ends of said lever arms for the purpose described. 50 55

FREDERICK WESTERBECK.
